US0D1113836S

(12) **United States Design Patent** (10) **Patent No.:** **US D1,113,836 S**
(45) **Date of Patent:** **** Feb. 17, 2026**

(54) **HAND CONTROLLER**

(71) Applicant: **Man Wah Intelligent Technology (Hui Zhou) Co., Ltd.**, Guangdong (CN)

(72) Inventors: **Zuochao Peng**, Guangdong (CN); **Zhuo Liu**, Guangdong (CN)

(73) Assignee: **MAN WAH INTELLIGENT TECHNOLOGY (HUI ZHOU) CO., LTD.**, Huizhou (CN)

(**) Term: **15 Years**

(21) Appl. No.: **29/937,083**

(22) Filed: **Apr. 12, 2024**

(30) **Foreign Application Priority Data**

Oct. 30, 2023 (CN) 202330703768.5

(51) **LOC (15) Cl.** **14-03**

(52) **U.S. Cl.**

USPC **D13/168**; D14/218

(57) **CLAIM**

The ornamental design for a hand controller as shown and described.

DESCRIPTION

FIG. 1 is a top, front and right side perspective view of a hand controller showing our new design;

FIG. 2 is a bottom, rear and left side perspective view thereof;

FIG. 3 is a top, rear and right side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof; and,

FIG. 9 is a bottom plan view thereof.

The broken lines in the drawings illustrate portions of the hand controller which form no part of the claimed design.

1 Claim, 9 Drawing Sheets
